(57) **CLAIM**

The ornamental design for a foot and toe washer, as shown and described.

DESCRIPTION

Application for utility patent, 10/639,138. The application was filed on Aug. 10, 2003.

FIG. 1 is a perspective view of a fully assembled foot and toe washer showing our new design.

FIG. 2 is a right side view thereof, the left side being a mirror image;

FIG. 3 is a top view thereof;

FIG. 4 is a bottom view thereof;

FIG. 5 is a (top) detailed view of portions thereof;

FIG. 6 is a (bottom) detailed view of portions thereof;

FIG. 7 is a detailed view of portions thereof;

FIG. 8 is a detailed view of portions thereof; and,

FIG. 9 is a perspective view of an alternate embodiment of our new design.
